Patented Sept. 14, 1920.

UNITED STATES PATENT OFFICE.

JOHN WILLIAMS, OF CLINTON, IOWA.

TRAIN-PIPE COUPLING.

1,353,006.

Specification of Letters Patent. Patented Sept. 14, 1920.

Application filed December 15, 1917, Serial No. 207,351. Renewed March 6, 1920. Serial No. 363,664.

To all whom it may concern:

Be it known that I, JOHN WILLIAMS, a citizen of the United States, residing at Clinton, in the county of Clinton and State of Iowa, have invented new and useful Improvements in Train-Pipe Couplings, of which the following is a specification.

The present invention relates to train pipe couplings; and it comprises, briefly, a device 10 of the class or character indicated having certain improved features of construction and arrangement which render it especially applicable for installation in the system of hose pipes or pipe sections in general use on 15 passenger coaches to supply steam heat from one coach to another, and as a result of which leakage between the coupling heads is entirely avoided and injury to the hose sections in the event of the train parting is 20 prevented.

According to the invention, the coupling heads at the confronting ends of a pair of hose sections are equipped with gaskets, as is usual; but these gaskets, instead of producing 25 openings or crevices between them, due to their shrinkage, are constantly maintained in steam-tight relation by being pressed forcibly toward each other to compensate for shrinkage, the devices imposing 30 such pressure upon the gaskets being so constructed and arranged as to be automatically detached therefrom immediately the coaches become uncoupled. Consequently, 35 the dangers to which both the train men and the passengers are ordinarily subjected—for example, the inability of either the engineer or the conductor and the passengers to see the station platform by reason of the escaping steam when the wind is in the proper 40 direction either in stopping or stepping off the train, and the liability of the train hands to become scalded in coupling and uncoupling the coaches—are completely eliminated, as well as the extra strain upon the 45 engine and the waste of steam and fuel.

An embodiment of the invention is illustrated in the accompanying drawing, wherein:—

Figure 1 is a side elevation, and Fig. 2 50 a plan view, showing the improved coupling in use; and

Fig. 3 is a vertical section on line 3—3, Fig. 1.

Referring more particularly to said drawing, 55 1 and 2 indicate diagrammatically the

confronting ends of a pair of passenger coaches, 3 and 4 the draw-bars between said coaches, and 5 and 6 the steam pipe or hose sections with which the coaches are equipped, all of which parts are or may be of the usual 60 character.

The confronting ends of the hose sections 5 and 6 are connected together, in turn, by means of the improved coupling members 7 and 8, the construction and arrangement 65 of the component parts of which comprise the subject matter of the invention, as previously stated. In the embodiment illustrated, which may be regarded for all practical purposes as preferred, each of said 70 members comprises a tubular neck or socket 9, in which the end of the corresponding hose section is inserted, a slightly larger tubular element or head 10, which is disposed in advance of and is integrally or 75 otherwise rigidly connected to the socket 9, and a cross-piece or plate 11, connected in a similar way to the head 10 and extending beyond the same at opposite ends. The forward or outer portion of each tubular head 80 10 is formed with an internal seat 12, here shown as frusto-conical or of gradually decreasing diameter from its outer to its inner end, to receive a similarly-shaped annular gasket 13. The latter projects slightly beyond the outer ends of their carriers or 85 heads 10, so that their confronting end edges are enabled to abut squarely against each other when the coupling is in use; rotation of the gaskets and consequent rubbing being 90 prevented by means, for instance, of internal keys or similar ribs or other projections 14 which are formed on the inner walls of the seats 12 and which fit into the key-seats or grooves 15 provided in the outer 95 walls of the gaskets, as represented in Fig. 3.

The two coupling members themselves are held against relative movement by securely attaching to each of the plates 11 a horizontal locking bar 16, the free end of which 100 slightly projects through a correspondingly-shaped opening 17 in the other plate. Besides serving that purpose, the locking-bars also serve to draw the cross-pieces or plates together and thereby maintain the abutting 105 edge faces of the gaskets in steam-tight relation so as to compensate for shrinkage; and to effect this, each bar has associated with it a pressure device 18 in the nature of a bent leaf spring or the like, each of 110

such devices being arranged vertically against the rear face of the adjacent cross-piece and having its terminals inserted through an opening 19 in the projecting end 5 of the adjacent locking-bar, which latter, as above explained, is fastened to the other cross-piece. Hence, it necessarily follows that the tension produced by the bending of the springs and their introduction through 10 the openings 19 will be exerted against the locking-bars and will tend to pull them in an endwise direction, and as a result, the two cross-pieces will be constantly pressed toward each other.

15 To uncouple the two members of the device, it is merely necessary to withdraw the springs 18, and this operation may, of course, be carried out directly by hand. It is preferable, however, to effect the operation 20 from a distance, in order to avoid danger of scalding, and it is equally desirable to have it take place automatically in the event of the train parting and thus prevent injury to the hose sections. According 25 to the present construction, the automatic withdrawal of the springs is effected by a pair of bell-crank levers 20, fulcrumed at their apices at 21 on brackets or other supports 22 fastened to the cross-pieces at diametrically opposite points. One 30 arm of each lever 20 extends toward the other coach, and is engaged at its terminal with the looped upper end of the adjacent spring so that when the lever arm moves upward it will lift up the spring with it, the said terminal of the arm being twisted 35 into a substantially horizontal position to enable its connection with the spring to be readily effected. The other arm of each 40 lever extends upwardly at an angle to the floor of the coaches, and is connected with the coach at the same side of the coupling by a chain 23, the latter being of such a length that while it is capable of permitting 45 the usual play between the draw-bars 3 and 4, the actual uncoupling of the coaches will immediately actuate the bell-crank levers; that is to say, said levers will be rocked by 50 the pull exerted upon them by the chains before the separation of the coaches imposes any stretching action upon the hose sections.

55 The purpose, operation and advantages of the invention are believed to be perfectly clear from the foregoing and further description and explanation thereof are, accordingly, omitted.

I claim as my invention:—

60 1. In a coupling for flexible pipe connections, the combination of a pair of tubular coupling heads each provided with an internal annular seat, a pair of gaskets fitted in said seats with their outer edge faces in abutting relation, locking means for the 65 heads consisting of reversely disposed ex-

tensions engaging the opposing heads at the extremities of the latter, spring means vertically disposed with relation to the outer side of each head and removably engaging with the extension of the opposing head, means for drawing the heads together and with which said spring means also engage, and means for automatically withdrawing the said spring means from association with their respective heads. 75

2. In a coupling for flexible pipe connections, the combination of a pair of tubular coupling heads each provided with an internal annular seat, a pair of gaskets fitted in said seats with their outer edge faces in abutting relation, each head having connected with it an extension which extends across and engages the other head, the said extensions projecting in reverse directions, means for drawing the heads together, and spring means associated with each head and removably engaging with the extension on the other head and with the means for drawing the heads together, whereby a constant pull on the two heads toward each other is instituted to maintain the abutting edge faces of the gaskets in fluid-tight relation. 90

3. In a coupling for flexible pipe sections, the combination of a pair of tubular coupling heads each provided with an internal annular seat, a pair of gaskets fitted in said seats with their outer edge faces in abutting relation, a locking bar connected with each head, the bars of the two heads extending in reverse directions across to the opposite head and slidably projecting through the latter to hold the heads against relative turning movement, and spring means movably associated with each head and terminally and withdrawably engaging the adjacent extremity of the locking bar for constantly pressing the heads toward each other and also permitting the heads to be disengaged during uncoupling operations. 105

4. In a coupling for flexible pipe sections, the combination of a pair of tubular coupling heads each provided with an internal annular seat; a pair of gaskets fitted in said seats with their outer edge faces in abutting relation; a cross-piece rigidly secured to each head; a locking member rigidly secured at one extremity to each cross-piece and having its opposite extremity slidably projecting through the other cross-piece to hold said heads against relative turning movement; and spring means associated with each cross-piece and engaged with the extremity of the locking member projecting therethrough for constantly pressing said cross-pieces and their connected heads toward each other, thereby to maintain the said abutting edge faces of said gaskets in fluid-tight relation. 115

5. In a coupling for flexible pipe sections, the combination of a pair of tubular cou- 120

pling heads having gaskets with their outer edge faces in abutting relation, a cross piece rigidly secured to each head, a locking lever movably associated with one extremity of each cross piece and having an arm extending across to and having its free extremity projecting through the other cross piece to hold the heads against relative turning movement, an opening lever associated with each head and provided with an arm extending across the opposite head, and spring means removably associated with the cross piece of each head to maintain the abutting edge faces of the gaskets in fluid-tight relation, each spring means being engaged by one of the opening lever arms for withdrawing said spring means from the portion of the head with which it engages.

6. In a coupling for flexible pipe sections, the combination of a pair of tubular coupling heads, a pair of gaskets carried by said heads with their outer edge faces in abutting relation, the heads having means extending across and engaging each other, a yielding presser device removably associated with each of the said means of the cross heads for constantly forcing the one head toward the other head to maintain the abutting edge faces of the gaskets in fluid-tight relation, and means also carried by the respective heads and engaging the yielding presser devices for withdrawing the latter from association with the means extending across from the respective heads and engaging the latter.

7. In a coupling for flexible pipe sections, the combination of a pair of tubular coupling heads; a pair of gaskets carried by said heads with their outer edge faces in abutting relation; spring means associated with each head and terminally extending through a portion of each head for constantly pressing the same toward the other head, thereby to maintain the said abutting edge faces of said gaskets in fluid-tight relation; and means for automatically withdrawing said spring means for association with their respective heads under predetermined conditions.

8. In a coupling for flexible pipe sections, the combination of a pair of tubular coupling heads; a pair of gaskets carried by said heads with their outer edge faces in abutting relation; a presser device associated with each head for constantly forcing the same toward the other head, thereby to maintain the said abutting edge faces of said gaskets in fluid-tight relation; and means for withdrawing each presser device from association with its respective head, embodying an operating lever with which said device is directly connected.

9. In a coupling for flexible pipe sections, the combination of a pair of tubular coupling heads; a pair of gaskets carried by

said heads with their outer edge faces in abutting relation; a presser device associated with each head for constantly forcing the same toward the other head, thereby to maintain the said abutting edge faces of said gaskets in fluid-tight relation; and means for withdrawing each presser device from association with its respective head, embodying a lever with which said device is connected, and a flexible operating element for said lever.

10. In a coupling for flexible pipe sections, the combination of a pair of tubular coupling heads; a pair of gaskets carried by said heads with their outer edge faces in abutting relation; a yielding presser device associated with and terminally extending through a portion of each head for constantly forcing the same toward the other head, thereby to maintain the said abutting edge faces of said gaskets in fluid-tight relation; and means individual to and operatively carrying each presser device and including a flexible operating element for withdrawing each presser device from association with its respective head.

11. In a coupling for flexible pipe sections, the combination of a pair of tubular coupling heads each provided with an internal, annular seat; a pair of gaskets fitted in said seats with their outer edge faces in abutting relation; a cross-piece rigidly secured to each head; a locking member connected to each cross-piece and slidably extending through the other cross-piece to hold said heads against relative turning movement; and a pair of oppositely-acting yielding presser devices engaged with said locking members for constantly forcing said heads toward each other, thereby to maintain the said abutting edge faces of said gaskets in fluid-tight relation.

12. In a coupling for flexible pipe sections, the combination of a pair of tubular coupling heads each provided with an internal, annular seat; a pair of gaskets fitted in said seats with their outer edge faces in abutting relation; a cross-piece rigidly secured to each head; a locking member connected to each cross-piece and slidably extending through the other cross-piece to hold said heads against relative turning movement; a pair of oppositely-acting yielding presser devices removably engaged with said locking members for constantly forcing said heads toward each other, thereby to maintain the said abutting edge faces of said gaskets in fluid-tight relation; and positive carrying means for said presser devices and operative to disengage said devices from the locking members.

13. In a coupling for flexible pipe sections, the combination of a pair of tubular coupling heads each provided with an internal, annular seat; a pair of gaskets fitted

in said seats with their outer faces in abutting relation; a cross-piece rigidly secured to each head; a locking member connected to each cross-piece and slidably extending through the other cross-piece to hold said heads against relative turning movement; a pair of oppositely-acting yielding presser devices engaged with said locking members for constantly forcing said heads toward each other, thereby to maintain the said abutting edge faces of said gaskets in fluid-tight relation; and means for automatically disengaging said presser devices from said locking members under predetermined conditions.

14. In a coupling for flexible pipe sections, the combination of a pair of tubular coupling heads each provided with an internal, annular seat; a pair of gaskets fitted in said seats with their outer edge faces in abutting relation; a cross-piece rigidly secured to each head; a locking member connected to each cross-piece and slidably extending through the other cross-piece to hold said heads against relative turning movement; a spring associated with each cross-piece and engaged with the locking member on the other cross-piece for constantly pressing said cross-pieces and their connected heads toward each other, thereby to maintain the said abutting edge faces of said gaskets in fluid-tight relation; and positive pivoted means in reverse positions on the cross-pieces for disengaging said springs from their respective locking members.

15. In a coupling for flexible pipe connections, the combination of a pair of tubular coupling heads provided with abutting extremities constructed to form a tight joint, locking means for the heads consisting of projections reversely extending from the respective heads and removably engaging correspondingly reversely positioned receptive means carried by the heads, and yielding means removably inserted through the said projections to hold the latter in connection with the receptive means and the abutting extremities of the coupling heads in fluid tight relation.

16. In a coupling for flexible pipe connections, the combination of a pair of tubular coupling heads provided with abutting extremities, locking means for the heads consisting of rigid projections reversely extending from opposite side portions of the respective heads and removably engaging correspondingly reversely positioned rigid receptive means carried by the heads, and yielding means removably inserted through the said projections and engaging portions of the receptive means to hold the projections in connection with the receptive means and the abutting extremities of the coupling heads in fluid tight relation.

In testimony whereof I have hereunto set my hand in presence of two subscribing witnesses.

JOHN WILLIAMS.
